CASE OR BOX

Filed Aug. 21, 1924

UNITED STATES PATENT OFFICE.

SAMUEL H. WISMER, OF PALMYRA, AND JOHN HENRY THAIDIGSMAN, OF DELANCO, NEW JERSEY, ASSIGNORS TO VICTOR TALKING MACHINE COMPANY, A CORPORATION OF NEW JERSEY.

CASE OR BOX.

Application filed August 21, 1924. Serial No. 733,285.

Our invention relates to cases and boxes adapted to contain and hold until desired for use, small articles, such as talking machine styli and other similar articles which are liable to be injured or damaged before being used if they are not properly protected.

One of the objects of our invention is to provide a relatively strong box or container with a holder for small articles, such as talking machine styli, said holder being mounted on the pintle of the hinge between the box proper and the lid, in such a manner that upon opening the lid, the holder is automatically swung upwardly away from the bottom of the box into an inclined position where the contents of the holder are accessible for withdrawal from the holder and so constructed that any liability of injuring the article in withdrawing the same from the holder is obviated.

A further object of the invention is to provide a holder in which the stylus is naturally and must be drawn straight-out of the holder; and to provide a guideway in the holder in which the stylus or similar article rests and is frictionally held and from which it is readily withdrawn without bending or twisting.

A further object of the invention is to provide a spring member preferably integral with the holder and which presses over a substantial portion of the length of the shank of the stylus so that the stylus is frictionally held in and is guided by said groove until the stylus is substantially clear of the holder.

A further object of the invention is to provide a holder in which any substantial sideways or lateral movement of the shank of the stylus with respect to the holder and any movement of the stylus therein by which the delicate point would be brought into engagement with a rigid portion of the holder and injured is prevented.

A further object of the invention is to provide a holder with a depression in which the small tungsten tip of a talking machine stylus is held in a fixed position in the holder, out of contact with the holder and on the underside of the holder below the plane of the surface on either side of the depression so that the tip of the stylus is

not liable to be caught upon any object and consequently bent or otherwise injured.

A further object of the invention is to construct a holder wherein a smooth uniform frictional grip on the stylus contained in the holder may be easily provided; and to provide a holder which has a pleasing attractive finished appearance, and so designed and arranged that uniform quantity production is possible as a manufacturing proposition.

Further objects of the invention will appear in the specification and claims below.

Referring now to the drawings forming a part of this specification and in which the same reference characters are employed throughout the various views to designate the same parts,

Fig. 1 is a plan view of the container with the lid open.

Fig. 2 is a plan view of the same with the lid closed, a part of the lid being broken away, however, to show the holder and a part of one of the resilient fingers or springs of the holder broken away to show how the stylus is held therein;

Fig. 3 is a vertical sectional view on the line 3—3 of Fig. 1;

Fig. 4 is a vertical sectional view on the line 4—4 of Fig. 2;

Fig. 5 is a plan view of the top side of the holder detached from the other parts of the container and with parts broken away to show the construction thereof;

Fig. 6 is a similar plan view of the bottom side of the holder or carrier with parts also broken away to make the construction clear;

Fig. 7 is a longitudinal vertical sectional view on the line 7—7 of Fig. 5;

Fig. 8 is a similar view on the line 8—8 of Fig. 5;

Fig. 9 is a view like Fig. 4 but with the carrier empty;

Fig. 10 is a top plan view of the stamping or blank from which the holder is made completed but for the bending up and over of the spring fingers and the coiling of the hinge projection;

Fig. 11 is a vertical sectional view on the line 11—11 of Fig. 10; and

Fig. 12 is a side elevational view on an enlarged scale, of a stylus for which the case and holder are particularly adapted

and showing the rounded surface thereof, adjacent the tip, abutting against the stop.

The main purpose of the present invention is to provide a convenient box or container for styli for use in connection with sound reproducing machines and particularly for those styli the minute record engaging tips of which are made or composed of a short length of tungsten wire or similar material rigidly secured to and projecting from the tapered end of a steel shank. These tungsten tips are easily bent if subjected to careless handling and when bent, the stylus is rendered unfit for reproducing sound from a sound record tablet. The delicate tips should protrude straight out from the end of the stylus and it is the object of the present invention to provide a carrier which will protect the tips of such styli until such time as they may be required for use. With this in view, we provide a relatively stiff box, preferably stamped up out of a sheet of metal and provided with a carrier or container in which the styli may be securely held, and protected from injury when not in use, and from which they may be readily withdrawn for use without injuring the tip in the act of withdrawing it from the holder, or in inserting it back into the holder.

50 The box or receptacle proper is preferably made of sheet metal and may consist of two parts, the box or box member 1 and the lid or lid member 2, hinged together along one edge of each of said members and preferably so that the flange of the lid member 2 fits over the edge of the box member 1. The terms lid and box are, however, relative terms for the said parts may be of any appropriate size, shape and proportion with respect to each other, and the carrier or holder 3 cooperating therewith in the manner to be described below may be made to swing with either the lid or the box proper.

The rear wall of the box may be provided with two hinge members 4—4 adapted to surround a pintle 5 and the rear wall of the lid may also and preferably be provided with two hinge members 6—6 also adapted to surround the pintle 5. The rear edge of the carrier or holder 3 may be similarly provided with a hinge member 7 adapted to fit around the pintle 5.

Preferrably, the hinge members 6—6 of the lid and the hinge member 7 of the carrier or holder tightly or snugly embrace the pintle 5, while the pintle 5 is preferably freely revolvable in the hinge members 4—4 of the box so that when the lid 2 is raised from the box 1, the pintle turns with the lid in the bearings provided by the hinge members 4 on the box, and the carrier 3, the hinge member 7 of which also tightly frictionally engaging the pintle, also turns with the cover or lid and the pintle, and the free swinging edge of the holder rises to a position

clear of the top edge of the box 1 so that the styli carried thereby are accessible for withdrawal from the holder.

The holder 3 is preferably an integral piece of metal stamped or cut and shaped out of a sheet of metal. The shaped blank completed except as to the bending of the projecting fingers upwardly and over parallel to the top side of the blank and the shaping of the hinge member, is shown in Fig. 10 and consists of a flat main portion 8 having a projection 7' on the rear edge thereof adapted to be later bent into the cylindrical hinge member 7 to tightly frictionally engage the pintle 5. The opposite or front edge of the main portion of the blank 8 is provided with a series of like equally spaced projecting fingers 9 so that when the main portion 8 is bent along the line 10—10, these fingers 9 will form the resilient springs of the finished carrier extending substantially parallel to the top surface of the main portion 8.

The main or body portion 8 is also preferably provided on its top side with a series of channels 11 preferably semicircular in transverse cross-section, each channel 11 being in axial alinement with a finger 9 respectively. Each groove or channel 11 terminates in holes or openings 12', 13, the centers of the openings 12' being arranged preferably on the line 10—10 of the bend to be made in the blank, or conversely the row of openings are so disposed in the main portion 8 as to provide a suitable line on which that part having the fingers 9 may be bent over. On the opposite side of the series of holes 13 is a series of short channels 14 preferably semicircular in cross-section and of smaller diameter than the grooves or channels 11. The said channels 14 are preferably pressed into the underside of the blank, and are disposed in axial alinement each with a groove or channel 11 respectively of the blank.

When the fingers 9 are bent upwardly and over through substantially 180° with the center of the bend on the line 10—10 shown in Fig. 10, the openings 12' will then be holes or openings 12 through the curved portion 15 connecting the body portion 8 with the spring fingers 9—9 and the centers of these openings 12 will be substantially in axial alinement with the axes of the grooves or channels 11—14. The outer ends 9' of the spring fingers 9 are preferably curved slightly upwardly away from the main or body portion 8, but the main portion thereof will be substantially parallel to the upper face of the main or body portion 8 particularly after the stylus 16 is inserted into the holder through the opening 12. When so inserted into the holder, the underside of the spring fingers 9 will bear evenly over a substantial portion of the length of the shank of the stylus.

A wire-tipped tungsten stylus 16, for

which the present holder is particularly adapted, is shown in Fig. 12 and comprises a shank portion 17, a tapered tip-holding portion 18 and a fine tungsten-wire recording tip 19, rigidly secured to the end of the tapered end 18. It is this tip 19 which is fully protected from injury by being positioned in one of the small channels 14. Because the holes 12 are at the front edge of the carrier 3, and because the shanks of the styli held therein protrude from the edge of the carrier, and because of the fact that the appearance of the holder so plainly indicates the position of the stylus with respect to the holder, the user most naturally inserts the styli straight into the holes 12 and draws them straight out of them. A stylus being inserted is guided by the channels 11 in which it is quite firmly held by the spring fingers 9, and finally the blunt rounded surface 18', closely adjacent the fine wire tip 19 comes into contact with the rigid abutment 20 formed at the end of the small channel 14 and the wall of the hole or opening 13, and further inward movement of the stylus is thus stopped. It can be pushed no further into the holder, and in this position, the other end of the shank 17 projects outwardly from the swinging or free edge of the holder through the opening 12, a distance sufficient to permit it to be readily grasped for withdrawal.

The holder attached, as above described, to the pintle 5 of the box, may be filled with as many styli as there are grooves 11 provided in the holder 3 and when the box is closed, the needles will be securely held in the holder and protected from accidental injury. When one wishes to use a stylus for reproducing sound with a talking machine, the lid is opened, and in opening the lid, the holder or carrier automatically swings with the lid and pintle upwardly bringing the free edge of the holder well above the top edge of the box until the upward movement of the holder is arrested by reason of the engagement of the rear edge 8' of the holder with the rear wall of the box, thus bringing the projecting ends of the shank 17 of the styli to a position where they are accessible for withdrawal from the carrier. But it is to be here noted that a stylus must be withdrawn straight out of the carrier in a direction coincident with the axis of the stylus, because the inner wall of the channel 11 fits closely around the shanks of the styli, because the fingers 9 hold the styli pressed down into the groove or channel 11, and because the diameter of the opening 12 is but slightly larger than the diameter of the shank of the stylus. These features of construction actually prevent the user from moving the stylus laterally or transversely in such a manner as to bring the fine reproducing tip 19 into engagement with any

rigid part of the holder. It is also to be observed that the diameter of the grooves or channels 14 are substantially less than the diameters of the shanks of the styli and preferably but a little greater than the diameter of the tips 19 so that when the stylus is completely inserted in the holder, the tip 19 is out of contact with anything and is protected by the thickness of the material of the holder, and the stop 20 is engaged by the blunt rounded surface 18' of the tapered end 18 of the stylus. The tip 19 is on the underside of the holder 3 and in the channel 14 of the holder. No fabric or any other thing can, therefore, easily catch on or strike against the slender reproducing tip of the stylus once it is properly inserted in the holder. It is protected on the upper side by the thickness of the holder and on the lower or under side by the box in which the holder is mounted.

The holders, as above described, are relatively easy to manufacture in large quantities. They may be accurately stamped and pressed uniformly up into the shape above described and shown in the drawings. No rigid part of the holder can engage the reproducing tip of the stylus in either inserting or withdrawing the stylus from the holder. The styli are preferably so firmly held in the holder that an appreciable amount of pull has to be exerted to withdraw a stylus from the holder so that when the stylus is released from the friction caused by the pressure of the spring fingers 9 on the shanks, the hand of the user will jump or jerk slightly in the direction of the pull, and quickly withdraw the stylus clear of the holder. It is difficult to do anything other than to continue to draw the stylus straight out of the holder after having once started to withdraw it therefrom.

Having thus described the invention, what we claim and desire to protect by Letters Patent of the United States is:

1. In a container for small articles, the combination of a box, a lid and a holder all pivoted together so that when the lid is opened the free edge of the holder swings above the edge of the box, said holder being provided with means to frictionally hold a small article with one end thereof projecting beyond the free edge of said holder and also with relatively rigid means to prevent the projecting end of said article from being substantially moved in a direction transversely to the axis of the article.

2. In a container for styli, the combination of a box, a lid and a holder pivotally mounted in said box and arranged so that when the lid is lifted the free edge of said holder is automatically swung above the top edge of said box, said holder being provided with means to hold a series of styli parallel and on one side of said holder with

the ends of the shanks of said styli protruding beyond the free edge of said holder, and relatively rigid means to prevent the insertion or withdrawal of said styli from said holder in any direction except substantially axially of said stylus.

3. In a container for styli, the combination of a box having a hinge member on one edge thereof, a lid having a hinge member on one edge thereof, a carrier having a hinge member on one edge thereof and a pintle to which said hinge members are secured, said carrier being provided with a channel in one face thereof in which the shank of a stylus fits and with an alined channel on the opposite side of said carrier in which the tip or point of said stylus may be positioned out of contact with said carrier, and means to frictionally hold a stylus in said first-mentioned channel with the end of said stylus protruding beyond the free edge of said carrier.

4. In a container for styli, the combination of a box, a lid and a carrier all hinged together along one edge of each thereof so that by opening the lid the free edge of said carrier is swung upwardly out of said box, said carrier being provided with a channel in one face thereof in which the shank of a stylus fits, with a resilient spring over and extending substantially parallel to the said channel to press against a substantial part of the length of a stylus seated in said groove to frictionally hold said stylus in said holder and with a channel on the opposite side of said carrier within which the tip or point of said stylus may be positioned out of contact with said carrier.

5. A holder for talking machine styli comprising a member provided with a channel in a side thereof in which a stylus is adapted to fit, with resilient means adapted to press against and frictionally hold a stylus in said channel, and with an opening therethrough in axial alinement with the axis of said channel and through which said stylus is inserted into and withdrawn from said member, said opening being slightly larger than the diameter of the stylus, and the wall of said opening being operative to prevent any substantial transverse movement of the stylus in withdrawing the stylus from and inserting it into said channel through said opening.

6. A holder for talking machine styli comprising a member provided with a channel in a side thereof in which a stylus is adapted to fit, with resilient means adapted to press

against and frictionally hold a stylus in said channel, with an opening therethrough in axial alinement with the axis of said channel and through which said stylus is inserted into and withdrawn from said member, said opening being slightly larger than the diameter of the stylus, and the wall of said opening being operative to prevent any substantial transverse movement of said stylus and with means against which the surface of the end of said stylus adjacent said tip abuts to limit the distance to which said stylus may be inserted into said holder through said opening.

7. A holder for talking machine styli comprising a member having a relatively flat surface provided with a channel, an edge of said member transverse to said channel being provided with a finger bent upwardly and over said flat surface to extend substantially parallel thereto and to frictionally engage the top of a stylus lying in said groove, the edge formed by said bent over portion having an opening therethrough in axial alinement with the axis of said channel and through which a stylus may be inserted into and may be withdrawn out of said groove.

8. A holder for talking machine styli comprising a member having a relatively flat surface provided with a channel, an edge of said member transverse to said channel being provided with a finger bent upwardly and over said flat surface to extend substantially parallel thereto and to frictionally engage the top of a stylus lying in said opening therethrough in axial alinement with the axis of said channel, said member being also provided with a transverse opening therethrough in which the inner end of said channel terminates, the opposite side of said member being provided with a small channel having its axis in alinement with the axis of said first-mentioned channel and also terminating in said transverse opening, the bottom of said small channel being out of contact with the tip of a stylus seated in said first-mentioned channel, the edge of said transverse opening providing a shoulder at the end of said small channel to engage the end of a stylus adjacent the tip or point thereof to limit the distance to which a stylus may be inserted into said first-mentioned channel.

In testimony whereof, we have hereunto set our hands this 19th day of August, 1924.

SAMUEL H. WISMER.
JOHN HENRY THAIDIGSMAN.
